UNITED STATES PATENT OFFICE.

DANIEL A. HAINES, OF PITTSBURG, PENNSYLVANIA.

MACHINE FOR CUTTING ICE.

SPECIFICATION forming part of Letters Patent No. 369,107, dated August 30, 1887.

Application filed September 17, 1886. Serial No. 213,839. (No model.)

To all whom it may concern:

Be it known that I, DANIEL A. HAINES, a citizen of the United States, residing at Pittsburgh, in the county of Allegheny and State of

5 Pennsylvania, have invented a new and useful Machine for Cutting Ice; and I do hereby declare the following to be a full, clear, and exact description of the invention, such as will enable others skilled in the art to which it pertains to make and use the same, reference being had to the accompanying drawings, which form a part of this specification.

My invention relates to a machine for cutting ice, the object being to provide a machine 15 of simple and durable construction, and operated by a hand-crank or by steam-power, if desired, whereby ice may be cut from a pond or other places in straight lines. This I accomplish by means of a circular saw mounted 20 on a suitable frame, together with certain other details of construction and combination of parts, as will be fully set forth hereinafter.

In the accompanying drawings, Figure 1 is 25 a side elevation of my improved ice-cutting machine, constructed in accordance with my invention. Fig. 2 is a plan view of the same.

To put my invention into practice and give the same bodily form, I construct a pair of skids or sled-runners, *a*, attached together by 30 a frame, *b*. Secured to this frame *b*, in suitable bearings, *c*, is a horizontal shaft, *d*, carrying a large pulley or belt-wheel, *e*, and having attached to one end a hand-crank, *f*. To this shaft *d*, I also hinge two arms, *g*, connected at the other end by a shaft, *h*, having secured thereto a large circular saw, *i*, and small pulley *j*. This pulley *j*, I connect to the large wheel *e* by a driving-belt, *k*. To the lower end of the arms *g*, I attach two handles, 40 *l*, which afford means for guiding the machine and pressing the saw *i* into the ice, *m*. At the rear end of the frame *b*, I hinge one or more sharp pieces, *n*, which remain at an angle with the frame *b*, and will allow the machine to be 45 easily pushed forward, but not back. Secured to the front shaft, *d*, is a small chain-pulley, *o*, which operates, by means of an endless driv-

ing-chain, *r*, a star-shaped wheel, *p*, secured in proper bearings at the base of the frame *b*, and affords a means of propelling the machine 50 forward.

The saw *i* and arms *g*, I suspend in any required position above the ice by means of a threaded prop, *s*, hinged to the rear of the frame *b*.

In operation the operators raise the handles *l*, and thereby lift the saw *i* above the ice and move the machine to the desired point to start from. The crank *f* is then revolved, which rotates the large wheel *e* and saw *i*. The operator at the handles *f* now presses the same down, which brings the saw *i* in contact with the ice, *m*, cutting its way down through the same. The star-shaped wheel *p* at the base of the frame *b* grips the ice and drags the machine forward, and the downwardly-projecting pieces *n* at the rear prevent any backward movement of the machine. In this way the apparatus moves forward, cutting the ice, *m*, in a straight line.

Having thus described my invention, what I claim, and desire to secure by Letters Patent, is—

An ice-cutting machine consisting of a sled mounted on runners, a propelling star-wheel 75 between the front runners applied on a shaft located below the driving-shaft *d* and receiving rotation therefrom by means of an endless chain and pulleys, a shaft bearing a circular cutter and receiving rotation from said driving-shaft, the vertically-movable arms *g*, bearing at their rear ends said cutter-shaft, the handles *l*, attached to the arms, said arms being vertically adjustable at their rear ends by means of a nut and screw, the latter being pivoted to the rear part of the sled, and the pieces *n*, hinged to the sled and adapted to resist backward thrust of this sled when the machine is in operation, all substantially as described.

DANIEL A. HAINES.
